(57) **CLAIM**

The ornamental design for an automatic spanking device, as shown and described.

DESCRIPTION

FIG. 1 is a top-front-right perspective view of an automatic spanking device showing my new design;

FIG. 2 is a bottom-rear-left perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a left elevated view thereof;

FIG. 8 is a right elevated view thereof;

FIG. 9 is a top-front-right perspective view thereof, showing the automatic spanking device with a mounting clamp;

FIG. 10 is a bottom-rear-left perspective view thereof, showing the automatic spanking device with the mounting clamp;

FIG. 11 is a reduced top perspective view thereof, showing the automatic spanking device in an operational configuration; and,

FIG. 12 is a reduced top perspective view thereof; showing the automatic spanking device in the operational configuration.

The broken lines showing of a user interface in FIGS. 1, 5, 7-9, and 11-12, the broken lines showing of a flexible arm end in FIGS. 1-4, and 6-9, the broken lines showing of paddles in FIG. 1-12, the broken lines showing of a clamp in FIG. 9-10, the broken lines showing of users in FIG. 11-12, the broken lines showing directional arrows in FIGS. 11 and 12, and the broken lines showing vibrational lines in FIGS. 11 and 12 are included for the purpose of showing environmental structure and form no part of the claimed design.

1 Claim, 12 Drawing Sheets
